TIE STRING APRON

Abraham S. Geisinger, Bronx, N. Y.

Application January 3, 1952, Serial No. 264,733

8 Claims. (Cl. 2—52)

My invention relates to aprons provided with tie string closure and securing means, and more particularly to the tie string itself.

Aprons provided with long tie strings always have been difficult objects to launder due to the tearing, entangling, and knotting of the tapes or strings in the washing and tumbling machines. In attempting to overcome these difficulties, the aprons have been provided with tubes to house retractable tapes, shortened elastic and Shirred tapes have replaced the common tape, and at times the tapes have been folded compactly and tied by manual operation prior to laundering. These, as well as other methods, have been tried but have not given satisfaction; the tube housing and retractable tape having increased the initial cost of the garment; the Shirred and elastic tape being sufficiently long also became entangled and knotted; and, manually tying the tape prior to laundering materially increasing the washing cost.

Therefore, my prime objective is to produce a minimum cost tie string apron, without tape housings and in which the tape needs no pre-washing handling and which will not become knotted and entangled during the laundering process.

Another object is to produce a tie string apron with a tie string or tape, capable of normal use but which when not functioning, remains in a restricted state and near the body of the garment.

A further object is to produce a tie string apron with a tie string or tape secured to the body of the garment in such manner as to permit normal use of the tape but restrict and limit its free movement during the laundering process.

I accomplish these and other objects by providing my apron with a tape, comprised of a tape element and an elastic and retracting and holding element, the tape element having a Shirred elastic portion intermediate tape portions and the tape element being secured at one end to the apron and intermediate its ends to the retracting element and the retracting element being secured at its ends to the tape element and to the apron at a position removed from the secured tape.

For further comprehension of the invention and of the objects and advantages thereof, reference will be had to the following description, the accompanying drawings and to the appended claims in which the various novel features of the invention are more particularly set forth.

Fig. 1 is a view of an apron with tie strings, embodying my invention. Fig. 2 is a fragmentary detail.

In the drawing and in the specifications, in which like numerals indicate similar elements, an apron 10 is shown formed with a body part 11, neck loop 12 and two similar tie strings 13, one being completely shown and the other indicated.

The tie strings 13 are positioned at opposite sides of the body of the apron and each tie string is comprised of a tape element 14 and an elastic contracting and retracting holding element 15.

An end of the tape 14 is stitched at 16 to the apron body near its edge and an end of the elastic element 15 is stitched at 17 to the apron body about five inches inwardly from the stitching 16. The tape element and the elastic contracting element are stitched together at 18, about five inches from the stitched ends 16 and 17, thus forming an equilateral triangle with the elements as sides and the distance between the stitched ends as the base.

It is evident from this structure that the tape at its 80 stitchings 18 is restrained from free movement except

2

within the limited area between the stitchings 16 and 17, although the tape at its stitchings 18 can actually be forced to a position five inches to the side of the stitching 16 removed from the stitching 17.

5 The tape element 14 is provided with a Shirred section 19 which extends outwardly from the stitching 18 towards the free end of the tape. The Shirring, which is formed by the tape being scalloped to the elastic element, permits this section of the tape to be extended or expanded to 10 more than double its six inch length. A free end 20 of the tape extends about nine inches beyond the Shirred section and provides material which can be used for tying the apron string. The tape in its contracted state is about twenty inches long, but only the fifteen inch length 15 beyond the stitching 18 can move freely. This fifteen inch length of free tape, however, is short enough, with the added stiffness due to the Shirring, to remain still and quiescent, comparatively, and not to become entangled or knotted with itself or other laundry during the washing and tumbling processes or to suffer excessive wear during the cleansing of the apron.

However, when desired, the tape element can be extended or expanded and pulled so as to become effective for its full length from the stitching 16 to its free end, 25 a distance of approximately thirty inches. As the apron is provided with two tie strings, each having such a tape sewn to the apron body edge, it is evident that even the largest waists easily can be encompassed.

It should be understood that although the specification 30 describes and the drawing shows the tapes as being sewn or stitched together or to the apron body at 18, 17 and 16, the parts so joined may be secured by other suitable means such as gluing, cementing, stapling or pinning, etc.

It should also be understood that although the dimensions 35 stated are preferable and produce an excellent product, other dimensions within the vicinity of those stated also can be used satisfactorily as well as proportionate dimensions.

In the detail shown in Fig. 2 a fragment of a tie string 40 21 is shown comprised of a tape element 22 and an elastic contracting and retracting holding element 23, which correspond, in general to the tie string 13 and its elements 14 and 15. In addition, the tape element 22 is secured to the elastic element by stitchings 24 corresponding to the 45 stitchings 18. However, a section 25, of the tie string 21, comprised of the tape and elastic elements sewn together, differs from the Shirred section 19 in that the elements are sewn together with the elastic element stretched or extended and by the laterally extending stitchings 26. This type of stitching is less costly and produces a more 50 efficient elastic extendable tape than the Shirred section 19. In all other respects and details and in its manner and method of being secured to the apron, the tie string 21 is similar to the tie string 13.

55 Although I have shown only a preferred embodiment and one variation of my invention, many other variations and changes are possible within the scope and concept of the basic idea of the invention. Therefore, I desire to cover all forms, modifications and embodiments of my invention which may come within the spirit and scope of any of the claims.

Having thus described my invention, what I claim as new and desire to secure by United States Letters Patent is:

- 65 In a tie string apron, an apron body portion, a tying means and a cooperating element, the tying means and cooperating element opposingly positioned on the apron body and together functioning to retain the apron in a normal wearing condition, said tying means comprised of a tape element and an elastic element, each said element being secured to the apron body at locations removed from one another, said tape element having intermediate its ends an extendable elastic section and said elastic element being secured to the tape element at an 70 approximate position on the tape element as far removed from the apron body as the length of the elastic element is when not elongated whereby the tape can be extended away from the elastic element when in use but otherwise will be limited in its free movement by the secured elastic element.
- 75 2. A tying means for an apron as described in claim 1

having its tape element provided with an elastic section suitable for extension and a terminal section suitable for tying, said sections being positioned at the free end of the tape.

3. A tie string apron, a tying means and a cooperating element and a body portion, the tying means and cooperating element opposingly positioned on the apron body and together functioning to retain the apron in a normal wearing condition, said tying means comprised of a tape element and an elastic element, said tape and elastic elements each being secured at one end to the apron body, the tape being secured in the vicinity of the apron body edge and the elastic element spaced approximately five inches therefrom, said tape and elastic elements being secured together for a distance of approximately six inches, in their unextended condition, and said joined together portion commencing approximately five inches from the joinder of each to the apron body and said tape having an end portion of approximately nine inches whereby the tape is restricted in its movement and extendable when desired.

4. In a tie string apron, an apron body portion, a tying means and a cooperating element, the tying means and cooperating element opposingly positioned on the apron body and together functioning to retain the apron in a normal wearing condition, said tying means comprised of a tape element and an elastic element, said elements each attached to the body part of the apron at locations removed from each other and the elastic element affixed to the tape element and the length of the portions of the tape and elastic element between their attached and affixed positions approximately being the same as the distance on the apron body between the attached elements whereby an approximate equilateral triangle is formed of part of the apron body, elastic element and tape element and free movement of the tape is prevented.

5. A tying means for an apron as described in claim 4, its tape element having a free end portion, said free end portion being positioned beyond the affixed elastic element and suitable for being secured to the cooperating element to retain the apron.

6. A tying means for an apron as described in claim 4, its tape element having intermediate its ends and further removed from the body than the affixed elastic element an expansible elastic section.

10 7. In a tie string apron, an apron body portion, a tying means and a cooperating element, the tying means and cooperating element opposingly positioned on the apron body and together functioning to retain the apron in a normal wearing condition, said tying means comprised of a tape element and an elastic element, each said element secured to the body part and to each other at approximately equal distances apart so as to form an approximate equilateral triangle, and said tape element having an elastic extendable portion, said portion approximately 15 commencing adjacent the location where the two elements are secured together whereby the tying means can be elongated for securing purposes or left retracted and contracted during laundering.

20 8. A tying means for an apron as described in claim 7, 25 its tape having a section suitable for securing purposes, said section positioned adjacent the elastic extendable portion and at the tape end.
